POURING ATTACHMENT FOR A CONTAINER

Richard D. Knapp, Rte. 3, Box 25-B,
Evergreen, Colo. 80439

Filed May 19, 1975, Ser. No. 578,910

Term of patent 14 years

Int. Cl. D9—07

U.S. Cl. D9—290

Fig. 1

Fig. 2

Fig. 3

Fig. 4

Fig. 5

FIG. 1 is a perspective view of the pouring attachment for a container showing my new design.

FIG. 2 is a top plan view thereof;

FIG. 3 is a side elevational view, the opposite side being identical to the one shown;

FIG. 4 is an end elevational view; and

FIG. 5 is a bottom plan view of the same.

I claim:

The ornamental design for a pouring attachment for a container, substantially as shown and described.
